[57] CLAIM

The ornamental design for an expandable core element for use with an injection molding system, as shown and described.

DESCRIPTION

FIG. 1 is a perspective view from above of the expandable core element for use with an injection molding system of our invention in the relaxed, expanded, non-molding position;

FIG. 2 is a perspective view from above of our invention of FIG. 1 in a closed, molding position;

FIG. 3 is a top plan view of our design of FIG. 1;

FIG. 4 is a bottom plan view of our design of FIG. 1; and,

FIG. 5 is a side plan view of our design of FIG. 1, the other side, front and back plan views being the same.
